UNITED STATES PATENT OFFICE.

ABRAM C. MOTT, JR., OF LANSDALE, PENNSYLVANIA.

TOP PLATE AND COVER FOR GAS-STOVES.

1,242,021.

Specification of Letters Patent.

Patented Oct. 2, 1917.

Application filed December 20, 1916. Serial No. 128,044.

To all whom it may concern:

Be it known that I, ABRAM C. MOTT, Jr., a citizen of the United States, residing in Lansdale, Montgomery county, Pennsylvania, have invented certain Improvements in Top Plates and Covers for Gas-Stoves, of which the following is a specification.

My invention relates to certain improvements in gas or oil stoves of the type having a top plate with openings above the burners and having supporting open work in the openings.

One object of my invention is to provide a solid removable plate adapted to close the opening when desired.

A further object of the invention is to make the open work section integral with the body of the plate and to provide bearing points flush with the upper surface of said plate and also to provide a cover plate having perforations through which the bearing points extend so that when the cover plate is in position its upper surface will also be flush with the top plate.

A still further object of the invention is to utilize the projecting elements of the fixed plate to retain the removable plate in position.

In the accompanying drawings:

Figure 1 is a perspective view of sufficient of a gas stove top plate to illustrate my invention, the detachable cover being shown in the elevated position;

Fig. 2 is a plan view of the fixed section of the plate;

Fig. 3 is an inverted plan view of the removable plate;

Fig. 4 is a sectional view of the fixed plate; and

Fig. 5 is a similar view showing the removable plate in position on the fixed plate.

Referring to the drawings, 1 is the top plate of a gas or oil stove having an opening 2 directly above the burner. In the present instance, over the burner is a series of radiating arms 3 made integral with the plate and having projections 4. These arms are connected by ribs 5 of the design clearly shown in Figs. 1 and 2, but it will be understood that the design of the open work may be modified without departing from the essential features of the invention. The projections 4 are preferably tapered, as shown, and are of such a height that the cooking

utensil placed on the stove will be supported by these projections on a level with the top surface of the top plate and there will be a clear space between the utensil and the radiating arms below the surface of the top plate.

6 is a detachable cover plate arranged to close the opening 2 and this plate has tapered openings 7, in the present instance, which register with the projections 4. The thickness of the cover plate 6 is equal to the height of the projections 4, as clearly shown in Fig. 5, so that when the cover plate 6 is in position it will be flush with the surface of the top plate 1 so that a cooking utensil located thereon will be at the same height from the burner as if the plate were removed and the utensil rested on the projections. The body of the cover plate is reduced in thickness and has an annular flange 8 connected to the radiating portions 9 in which are formed the holes 7.

While I have illustrated the projections arranged in a given manner and the open work having a certain ornamentation, it will be understood that the design may be modified without departing from the spirit of the invention.

The openings in the cover plate 6 are of such size and shape as not to materially weaken the plate so that it will not buckle when subjected to heat.

I claim:

The combination of a top plate for a gas or oil stove having an openwork supporting structure depressed below the surface of the top plate and having a series of small tapered projections thereon terminating on a plane with the upper surface of the top plate, the openwork structure being cast integral with the plate; and a detachable cover plate arranged to be mounted upon the openwork structure, the top surface of said cover plate being even with the top plate of the stove and having a series of radiating ribs on the under surface, the plate having a series of holes at the ribs for the reception of the projections on the supporting structure of the top plate of the stove so that when the cover plate is in position its surface will be on the same plane as the upper surface of the top plate of the stove.

ABRAM C. MOTT, JR.
